UNITED STATES PATENT OFFICE.

JOSEPH M. ATKINSON, OF BALTIMORE, MARYLAND, ASSIGNOR TO OPPENHEIM, OBERNDORF & CO., INC., OF BALTIMORE, MARYLAND, A CORPORATION OF MARYLAND.

UNION GARMENT.

1,410,870.

Specification of Letters Patent. Patented Mar. 28, 1922.

Application filed April 2, 1919. Serial No. 286,855.

To all whom it may concern:

Be it known that I, JOSEPH M. ATKINSON, a citizen of the United States, residing at Baltimore, in the State of Maryland, have 5 invented certain new and useful Improvements in Union Garments, of which the following is a specification.

This invention relates to improvements in union garments and is directed particularly to garments wherein elastic inserts are 10 employed to provide elasticity at places in the garment where strains are applied.

The object of the invention is to provide 15 improved reinforced elastic webbing inserts at the back of a union garment whereby vertical and horizontal elasticity will be provided and at the same time the elastic which provides the horizontal elasticity will serve as a reinforce in a vertical direction while 20 the elastic which provides vertical elasticity will serve as a reinforce in a horizontal direction.

Another object is to provide an improved 25 construction and arrangement of reinforcement for elastic garment inserts.

The invention is illustrated in the accompanying drawing wherein,—

Fig. 1, shows a union garment in rear view to which my improvement is applied.

Fig. 2, illustrates on an enlarged scale a 30 fragment of an elastic insert provided with my improved reinforcement, together with fragments of the woven or inelastic garment fabric at each side of the elastic insert.

Fig. 3, shows a vertical longitudinal section through the vertical elastic insert as the same would appear if cut on the line 3—3 of Fig. 1, and

Fig. 4, illustrates a horizontal sectional 40 detail through the horizontal elastic insert, —the section being taken on the line 4—4 of Fig. 1.

Referring to the drawing the numerals 5 and 6 designate two body parts of the 45 rear of the garment and 7 and 8 the two rear leg parts of the same.

The front of the garment is not illustrated but may be of the usual construction and parts, which however, are joined to the rear 50 parts by vertical side seams 9.

A posterior flap 10, is provided on the rear leg parts, and a button or equivalent fastening 11, is employed to secure the flap in position.

Between the two upper body parts 5 and

6 and the two lower leg parts 7 and 8 I interpose a crosswise strip of elastic webbing material 12. This elastic webbing strip extends from one side seam 9 to the other and has its upper edge stitched along the 60 lines 13 and 14, to the lower edges of the upper body parts 5 and 6 respectively and has its lower edge secured by stitching 15, across the upper edges of the rear leg parts 7 and 8. 65

Intermediate its ends, the elastic strip 12, is provided with two vertical folds 16 and 17 respectively,—one of said folds 16, being located on the outer side of the garment and the other on the inner side of the 70 garment. This double fold in the elastic strip produces a three ply thickness between the two vertical folds 16 and 17.

At the vertical folds 16 and 17, the three-ply thickness of elastic webbing material 75 is secured together by spaced-apart vertical rows of zig-zag stitching 18, which latter, while securing the three plies of material together do not destroy the elasticity in a vertical direction. 80

By reference to Fig. 1, of the drawing it will be noted that the double folds 16, 17 and the three ply thickness of elastic material are located at a point on the rear of the garment in a vertical plane between the 85 inner edges 19 and 20 of the two upper body parts 5 and 6 of the garment so that, in this instance, the reinforcement formed by the triple fold is not directly interposed between either upper body part and the lower 90 leg parts.

It will also be noted by reference to Fig. 1, that the upper end 21, of the flap 10, terminates at the lower seam or stitch line 15, and at one side of the three ply reinforcement. 95

Between the two upper rear body parts 5 and 6, I interpose a strip of elastic material 22, which latter has its opposite vertical edges secured to the inner vertical 100 spaced-apart edges 19 and 20 of the two upper body parts. This elastic strip therefore extends vertically between the two rear body parts with its upper edge formed into a fold 23, at the neck opening 24, and its lower edge 25, secured to the upper edge of the cross-wise elastic strip 12, at the three-ply reinforce and between the vertical folds 16 and 17 of the strip 12. 105

This construction secures the lower end 110

of the vertically-inelastic strip 22, at the upper edge of the horizontally-inelastic strip so that vertical strains on the vertical strip will cause the horizontal strip to yield 5 vertically at the reinforced three-ply central point.

The vertical strip 22, which is horizontally elastic because it is formed of elastic webbing that will stretch in one direction 10 but is substantially inelastic in the other direction has two horizontal or cross-wise folds 26 and 27,—the former at the outer side of the garment and the latter at the inner side of the garment as clearly shown 15 in Fig. 3, of the drawing.

This double fold also produces a three-ply thickness of elastic material between the two rear body parts 5 and 6 and also between the neck and the cross-strip 12. This 20 reinforcement is therefore located between the shoulders or arm holes where horizontal strains in the garment are greatest.

This three-ply reinforcement in the vertical strip 22, is also maintained by zig-zag 25 spaced rows of stitches 28, which secures the plies against vertical strains but leaves the strip elastic to yield for cross-strains.

By means of this peculiar arrangement 30 of elastic strips and reinforcements I produce a garment that is peculiarly elastic both vertically and horizontally and is also reinforced in both of said directions and by this means a closer fitting and less bulky garment can be produced with a saving of 35 material.

It will also be seen that the reinforcement in both elastic strips is formed by folding the elastic webbing material upon itself and producing a plurality of return bends therein, thereby avoiding patches or 40 separate pieces of webbing and the inconvenience in handling raw edges which such patches must have.

Having described my invention, I claim,—

1. A union garment having a rear with 45 two upper body-parts which are separated by a central vertical strip of elastic material whose upper end terminates at the neck-opening,—said vertical strip being folded horizontally at a plurality of points to produce a plurality of plies between the folds from the single strip and means for elastically securing the said folds in a horizontal direction.

2. A union garment having a rear with 55 two upper body-parts that are separated by a vertical elastic strip and two lower leg parts whose upper edges are attached to the lower edge of a horizontal elastic strip,—the upper edge of said horizontal strip 60 being secured to the lower edges of the two upper body parts and also to the lower edge of the vertical elastic strip and both elastic strips having at least two cross-folds which extend in a direction in which the 65 strips stretch and the folds in each strip being secured by elastic stitching.

In testimony whereof I affix my signature.

JOSEPH M. ATKINSON.
